CLAIM

The ornamental design for an illuminative artificial nail, as shown and described.

DESCRIPTION

FIG. 1 is a perspective view showing my new design in use.
FIG. 2 is a top plan view thereof.

FIG. 3 is a right side view thereof, the left side view being a mirror image thereof.

FIG. 4 is a bottom view thereof.

FIG. 5 is an end view thereof; and,

FIG. 6 is a perspective view of the invention on an artificial nail.

The broken line showing of the human form is for illustrative purposes only and forms no part of the claimed design.
